UNITED STATES PATENT OFFICE.

THOMAS E. CHERRY, OF REVERE, MASSACHUSETTS.

PUMP.

No. 918,007.

Specification of Letters Patent.

Patented April 13, 1909.

Application filed May 7, 1908. Serial No. 431,485.

To all whom it may concern:

Be it known that I, THOMAS E. CHERRY, of Revere, in the county of Suffolk and State of Massachusetts, have invented certain new and useful Improvements in Pumps, of which the following is a specification.

This invention relates to pumps for circulating water, although it may be used for raising or circulating other liquids, or even 10 air, or other gaseous fluids.

The object of my invention is to provide a simple, compact and effective pump which will supply a steady and continuous stream, or, circulation, only an absolutely even application 15 of power being necessary to operate the pump.

To this end my invention consists in a pump having a circular series of parallel cylinders and pistons surrounding a central duct 20 for the fluid, the said duct communicating with the cylinders, the pistons being operated successively or one following the other, in rotation.

My invention further consists in subordi- 25 nate improvements, as will be more fully hereinafter described and claimed.

Of the accompanying drawings in which similar reference characters indicate the same or similar parts in all of the figures:—
30 Figure 1 represents a partial elevation, and partial longitudinal section of a pump embodying my improved construction. Fig. 2 represents a section through the pump on the line 2—2 of Fig. 1. Fig. 3 represents a detail 35 section on line 3—3 of Fig. 1. Fig. 4 represents a different arrangement of valve mechanism hereinafter explained.

A circular casing 10, supported on a suitable base 11, has its middle portion between 40 its ends bored or otherwise constructed to form a plurality or series of cylinders 12, said cylinders being parallel with each other and with the longitudinal center of the casing and equidistant from the said longitudinal center.

45 One end of the casing (the left-hand end in Fig. 1) is externally reduced in diameter to form an extension 13. The extension 13 may be integral with the portion 10, but for convenience of manufacture it is separate 50 from, but secured to the portion 10 by suitable means, such as bolts 14.

On the extension 13, is mounted a pulley 15 through the medium of which the pump is driven. The said extension 13 contains 55 within it a cam hub 16 which is formed with a cam groove 17, said hub 16 being connected

to the pulley 15 so as to be rotated by it as best shown in Fig. 2. The cam hub 16 fits closely within the casing extension 13, and the latter is formed with a series of internal 60 longitudinal grooves 18 which receive and guide the piston rods 19 of the pistons 20 which latter are mounted and reciprocate in the cylinders 12, the pistons 20 being, of course, provided with suitable packing, as 65 shown in Fig. 1. Each piston rod is provided with a pin 21, preferably provided with a roller, and entering the cam groove 17. As will now be readily understood, when the pulley 15 is rotated as by means of a belt driven 70 by hand or any suitable motor, the hub 16 is rotated so that this groove causes the piston rods and pistons to reciprocate in their cylinders, their motion being such that they follow each other in succession. In the 75 pump, illustrated in the drawings, there are seven cylinders and pistons and consequently there will always be at least two of them moving in the same direction, one behind the other in order of operation. 80

Leading into the end of the casing, opposite the pulley, is an inlet 22, the said inlet connecting with a chamber 23 formed in the end wall of the casing. The said end wall 24 is formed with as many ports 25 as there are 85 cylinders, said ports connecting the chamber 23 with passages 26, each of the latter being connected at 27 with a cylinder 12. A port 28 opposite each cylinder 12 connects with a central chamber 29 which latter connects 90 with the central duct for the outflow, of the fluid. Each port 25 is provided with a valve 31 which valve is seated by a spring 32. Each port 28 is furnished with a valve 33, seated by a spring 34. A pin 35 has its ends 95 projecting toward the ports 25 and 28, the valves being mounted to slide on said ends. Said valves are also preferably provided with guide pins 36 which enter the ports.

In operation the rotation of the pulley 15 causes the cam to actuate the pistons in succession, each piston drawing in fluid through the inlet 22, port 25 and passage 26, and opening 27 into the cylinder. Then on the return of the piston the fluid is ejected from 100 the cylinder and through the port 28 into the chamber 29 and through the outlet or central duct 30, the two valves for each cylinder opening and closing alternately under the influence of the fluid pressure and of the valve 105 springs.

Owing to the fact that the outlet com-

prises a duct which is central relatively to the circular series of parallel cylinders and pistons, the mechanism of the pump is kept cool by the fluid being pumped, especially when the latter is water. The resistance to the power employed in operating the pump is absolutely uniform because of the number of cylinders and pistons employed, all of which follow each other, or operate in succession.

I have shown in Fig. 4 an arrangement of the valve mechanism to be substituted for that shown in Fig. 1, which is more effective when pumping air, as the space between the inlet valves and the pistons is reduced to the minimum. To this end I provide the end wall 24, having the inlet 25, and valves 40 and outlet valves 41, and attach the same to the casing 10 by bolts 14.

20 I claim:—

1. In a pump, a stationary solid casing having a circular series of parallel cylinders formed therein, pistons in said cylinders and having piston rods, a hub rotatively mounted in the space between said piston rods and having a cam, operative connections between said cam and the piston rods, and a pulley surrounding the piston rods and operatively connected with the cam hub.

2. In a pump, a stationary solid casing having a circular series of parallel cylinders formed therein, and having a cylindrical extension at one side, a pulley mounted on said extension, a cam hub within said extension and operatively connected with said pulley, and pistons in said cylinders, said pistons having rods projecting between the said extension of the casing and the cam hub and operatively connected with the latter.

3. In a pump, a stationary solid casing having a circular series of parallel cylinders formed therein, and having a cylindrical extension at one side, said extension having a series of internal longitudinal grooves, a pulley mounted on said extension, a cam hub within said extension and operatively connected with said pulley, and pistons in said cylinders, said pistons having rods fitting the

internal grooves of said extension of the casing and operatively connected with the latter. 50

4. A pump comprising a casing having a circular series of parallel cylinders and pistons, a pulley mounted on said casing, a hub located between said pistons and having a cam groove, said hub being operatively connected with said pulley, the said pistons having their rods provided with pins entering said cam groove, a central longitudinal outlet duct extending between the operating parts of the pump and serving to cool the same, 60 and valved inlet and outlet ports for said cylinders.

5. A pump comprising a casing having a circular series of parallel cylinders and pistons, a pulley mounted on said casing, a hub 65 located between said pistons and having a cam groove, said hub being operatively connected with said pulley, the said pistons having their rods provided with pins entering said cam groove, a central longitudinal outlet duct extending between the operating parts of the pump and serving to cool the same, 70 a valved port leading from each cylinder to said outlet duct, and means for supplying fluid to said cylinders. 75

6. A pump comprising a casing having a circular series of parallel cylinders and pistons, a pulley mounted on said casing, a hub located between said pistons and having a cam groove, said hub being operatively connected with said pulley, the said pistons having their rods provided with pins entering said cam groove, a central longitudinal outlet duct extending between the operating parts of the pump and serving to cool the 80 same, a valved port leading from each cylinder to said outlet duct, a single inlet, and a valved port leading from said inlet to each cylinder. 85

In testimony whereof I have affixed my 90 signature, in presence of two witnesses.

THOMAS E. CHERRY.
